DISPLAY DEVICE FOR SUCCESSIVELY EXHIBITING DIFFERENT DISPLAYS

Richard E. Paige, New York, N.Y., assignor to Paper Products Development Corporation, New York, N.Y., a corporation of New Jersey

Filed Mar. 26, 1964, Ser. No. 354,999
8 Claims. (Cl. 40—81)

This invention relates generally to display devices, and has particular reference to an apparatus primarily intended for advertising purposes and adapted to exhibit different display surfaces in a continuous repetitive sequence.

It is a general object of the invention to provide a display device that can be inexpensively manufactured in commercial quantities, and operated at low cost by means of a small inexpensive motor deriving its power from a simple array of dry cells or from any conventionally available electric current source.

A more particular object of the invention is to provide a device of the character described whose structure consists essentially of inexpensive sheet material such as cardboard, and which will operate reliably for extended periods of time.

Another object is to provide a device of the foregoing character in which display panels are used in such a way that they can be readily changed or replaced.

The display device to which the invention relates consists essentially of a shallow rectangular container mounted for continuous slow rotation about a central horizontal axis whereby the opposite ends of the container are alternately raised to a position above the axis of rotation, there being an odd number ($2x+1$) of display panels within the container adapted to slide successively and by gravity from one end region of the container to the other as the container rotates. The two main walls of the container are provided with display openings in symmetrical relation to the axis of rotation, and the functioning of the device is such that successive exhibition through these openings of all surfaces ($4x+2$) of the display panels is achieved. The display effect is attention-arresting, since the mode of operation is not readily apparent to a viewer.

The continued operation of such an apparatus in reliable trouble-free fashion depends upon a maintenance of precise container dimensions and configuration, smoothly balanced rotational movements, and an unimpeded sliding relationship among the display panels. This presents an unusual problem when the container and the panels are to be fabricated of cardboard or similar sheet stock, since such a material is not always dimensionally stable, not absolutely rigid, and is susceptible to warping and distortion. The unusual features of the invention relate to a solution to this special problem, and hence to the provision of a display device which has all the desirable operational characteristics described, and which is staunch and reliable in use despite the fact that it is constructed essentially of light-weight non-metallic sheet material which would ordinarily be unsuitable to meet the demands of an apparatus involving relatively movable elements requiring precise dimensions and contours.

One of the features of the invention resides in furnishing the container in the form of a shallow cardboard box composed of conventional opposed sections each of which has a relatively large main wall and relatively narrow peripheral walls, the sections being telescopically interfitted so that the peripheral walls lie in overlapping relation and define two-ply side and end walls on the box. Such a box can be made at low cost, and in commercial quantities, on conventional automatic box-making machines.

2

Another feature lies in securing the box, at its central region, to a rigid metal rod which extends horizontally across the interior of the box with its ends projecting out through the opposed side walls. A means is provided for securing the rod to at least one of the side walls and for supporting the rod ends for rotation of the rod on its axis, so that by slowly rotating the rod the box can be caused to undergo a corresponding balanced rotation with a minimum of strain and distortion.

10 A further feature of the invention resides in furnishing the display panels in the form of simple paperboard elements, bearing lithography or other embellishment on each surface, and in providing each panel with special enlarged stiffeners along its edges. The stiffening elements have smoothly rounded contours and are preferably elements of C-shaped cross-section, each element being slidably applicable to a panel edge to enclose the edge within the confines of the C-shaped element.

One way of attaining these general objectives, and 20 such other objects and advantages as may be pointed out hereinafter, is illustrated in the accompanying drawings, in which:

FIG. 1 is a perspective view of a display device embodying the features of the invention;

25 FIG. 2 is an enlarged perspective view of one of the display panels by itself;

FIG. 3 is a cross-sectional view substantially along the line 3—3 of FIG. 1;

30 FIG. 4 is a cross-sectional view substantially along the line 4—4 of FIG. 1;

FIG. 5 is a cross-sectional view along the line 5—5 of FIG. 4; and

35 FIG. 6 is an enlarged fragmentary view of the lower end of the box as shown in FIG. 3.

In the display device chosen for illustration, the box containing the display panels is indicated generally at 10, and the support within which it is mounted for rotation is designated 11. One of the panels is shown by itself in FIG. 2 and is designated by the reference number 12.

As best indicated in FIGS. 3, 4 and 5, the box 10 comprises a pair of opposed sections 13 and 14. The section 13 has a main rectangular wall 15 and a relatively narrow upstanding peripheral wall 16. Similarly, the section 14 has a main rectangular wall 17 and a relatively narrow upstanding peripheral wall 18. The sections are of such dimensions that the peripheral walls 16 and 18 can be brought into snug overlapping relation as the sections 13 and 14 are interfitted in a telescopic manner to define the box.

45 A box of this character can be readily manufactured, at relatively low cost, and in commercial quantities, on conventional box-making machinery. It will be noted that the overlapping peripheral walls 16 and 18 define two-ply end and side walls on the box.

The two sections of the box are not permanently interengaged. They fit snugly, one within the other, but it is contemplated that they may be separated to allow access to the interior of the box, for replacement of display panels or other purposes, whenever it is removed from its supporting structure 11.

50 Each of the end walls of the box is provided, on the interior, with a cushioning layer of rubber or its equivalent, designated 19 in FIGS. 3 and 6.

65 Extending transversely across the box, at its center, is a horizontal metal rod 21. Its ends extend outward through the opposed side walls of the box. One of these ends (the one shown at the right in FIGS. 4 and 5) is adapted to be inserted into an appropriate eyelet or equivalent bearing 22 within which it is journaled. The opposite end of the rod is insertable into a metallic sleeve 23 provided with a set-screw 24 adapted to engage the rod end in a

releasable manner. The sleeve 23 is provided with an attachment part 25 rigidly secured to the adjacent side wall of the box. This securing may be accomplished in any suitable manner, and one satisfactory way is to rivet it to the outer ply of the side wall. This is important, because there should be no rivet head or other projecting piece on the interior of the box.

By means of the sleeve 23, the attachment part 25, and the set-screw 24, the rod 21 is securely joined to the box in such a way that slow rotation of the rod 21 will impart a corresponding rotation to the box as a whole. This can be achieved by providing the sleeve 23 with an extension provided with another set-screw 26, this extension being adapted to receive and engage a driving shaft 27. In the illustrated embodiment, this shaft projects toward the rod 21, in alignment therewith, from the opposite upright of the supporting structure 11. The shaft 27 is part of a small electric motor 28, such motors being well known in the art and being driven by a conventional 110-volt current. The electrical connector for the motor 28 is indicated at 29, and may extend out of the supporting structure 11 through an opening 30 provided for this purpose. The motor 28 is secured to the interior of the supporting structure in any suitable manner.

As best indicated in FIG. 3, the main box wall 15 is provided with a display opening 31, and the box wall 17 is provided with a similar display opening 32. These openings are preferably rectangular and of substantial size, and they are symmetrically arranged with respect to the axis of the supporting rod 21. That is to say, the display opening 31 is adjacent to one end of the box structure, while the display opening 32 is adjacent to the opposite end. When the box is rotated as indicated by the arrows 33 in FIGS. 1 and 3, each of the display openings 31 and 32 presents itself in the upper part of the display apparatus when it is viewed from the side depicted in FIG. 1. This may be considered the front of the display device.

Accommodated within the box 10 there is an odd number $(2x+1)$ of rectangular display panels. Preferably they are five in number, as indicated in the drawings. Each panel consists of a substantially rectangular paperboard or cardboard sheet 37 bearing lithography or printing or other embellishment on each of its faces. For stiffening purposes, among others, each edge of the element 37 is engaged by a stiffening element that is slidably applicable to it. As best shown in FIG. 2, the stiffening elements 35 along the upper and lower edges extend for the full length of these edges, while the stiffening elements 36 engaging the side edges extend between the elements 35.

Each reinforcing element is smoothly rounded and somewhat enlarged with respect to the thickness of the sheet 37. Essentially, each reinforcement is an element of rigid plastic or the like, having a substantially C-shaped cross-section. It is of such dimensions, preferably slightly springy, that it frictionally grips the edge to which it is applied, and completely encircles the edge.

The box 10 has a depth, between the main walls 14 and 15, substantially equal to $(x+1)$ of the display panels. This means that where the display panels are five in number, the depth of the box is such that it will accommodate, at most, three of the panels in superposed relation. This is best indicated at the lower end of FIG. 3.

The panels 12 are of such dimensions that they occupy end regions of the box, on one or the other side of the central rod 21. The dimensions of the panels are related to the display openings 31 and 32 so that the embellishment on the surface of each panel will show through the display opening with which it comes into registry from time to time as the box rotates.

The operation of the device can best be described by assuming, to start, that the display panels are in the relationships shown in FIG. 3, there being three of the panels at the lower end of the box, two at the top. As viewed in FIG. 3, the display panel at the top which is at the right shows through the display opening 32. It is supported in this position by the circumstance that its

lower reinforced edge rests upon and is supported by the upper reinforced edge of the display panel directly beneath it. The other display panel at the top of the box is retained in its elevated disposition because its lower edge rests against the rod 21. (If there are more than five display panels, those panels which do not encounter the center rod at any instant of time will rest upon the panel directly beneath.)

As the box rotates in a counter-clockwise direction from the position shown in full-lines in FIG. 3, the panels designated A and B ultimately reach and pass through the position shown in dot-and-dash lines in FIG. 3. The panel A is now in alignment with the display opening 31 as this opening gradually comes into the field of view of the person standing in front of the device. The panel B remains directly behind the panel A and is shown slightly higher because its lower end (not shown) is resting against the rod 21. The panel C, however, has started to slide to the opposite end of the box, i.e., the end which is now the lower end, as indicated by the arrow 34. When the box reaches the vertical position, there will be (as shown in full lines) two display panels at the top and three at the bottom. Those at the bottom will now be (from left to right as viewed in FIG. 3) panels C, D, and E.

During the next succeeding 180° rotation of the box, a face of the panel C will become visible to the viewer through the display opening 32. As the box continues to rotate, successive panels will become visible through one or the other display opening, and the functioning of the apparatus is such that each embellished surface of each panel becomes visible in succession. Thus a total of $(4x+2)$ display surfaces is exhibited, one after the other, the operation then repeating itself.

The features of the invention that make it possible to construct the apparatus of inexpensive cardboard or the like and yet achieve reliable functioning over long periods of time include the central rigid rod 21 which assures a balanced, smooth, and undistorted action, the double-ply nature of the peripheral walls of the box affording added strength in these regions, and the rigidifying stiffeners 35 and 36 on each display panel. These stiffeners not only maintain each panel in a true plane, thus overcoming any tendency to warp or distort, but they also facilitate the sliding movements hereinbefore described and protect each embellished face of each panel from rubbing contact with any of the other display faces.

The cushioning elements 19 at the opposite ends of the box contribute to silent operation, and minimize any shock that might impair smooth reliable functioning of the device.

It will be understood that the supporting structure 11 may be of any suitable kind. That chosen for illustration is composed of sheet material, such as cardboard, cut, scored, and assembled to define a substantially U-shaped supporting structure of hollow character. This is desirable from a standpoint of economy, but the details of this structure do not form any part of the present invention.

Whenever it is desired to change or replace the display panels within the box, the set-screws 24 and 26 are loosened, whereby the sleeve 23 may be slipped off the drive shaft 27. This makes it possible to withdraw the opposite end of the rod 21 from the journal 22 and to withdraw the rod from the box 10. The box 10 can then be opened. A reassembly of the parts is accomplished by a reversal of these steps.

It will thus be seen that a display device has been provided which has a unique and attention-arresting mode of operation, which is composed of relatively inexpensive stock and can therefore be manufactured in large quantities at low cost, and which will function reliably without requiring any attention other than to change the display panels from time to time. While an electric motor has been considered to be preferable for rotating the device, other types of motors (or even manual operation) might

be employed. Where an electric motor is used, the source of power may be batteries or house current, as may be desired.

In general, it will be understood that many of the details described and illustrated may be modified by those skilled in the art without necessarily departing from the spirit and scope of the invention as expressed in the appended claims.

What is claimed is:

1. In a display device:

a shallow rectangular cardboard box composed of opposed sections each of which comprises a relatively large main wall and relatively narrow peripheral walls, said sections being telescopically interfitting so that said peripheral walls lie in overlapping relation and define two-ply side and end walls on the box,

a rigid rod extending horizontally across the center of said box with its ends projecting out through the telescoped sections of the opposed side walls thereby constituting means for locking said opposed sections, means for securing said rod to at least one of said side walls, means for supporting said rod ends for rotation of the rod on its axis, and means for slowly rotating said rod so that the box will rotate and bring its opposite end walls alternately to a relatively raised position,

each main box wall having a display opening, said openings being symmetrically arranged with respect to the rod axis,

an odd number $(2x+1)$ of rectangular cardboard display panels within said box, each being of a size to fit within one half of the box on one or the other side of said rod, said panels bearing display indicia on each of their faces,

the box depth between its main walls being just sufficient to accommodate $(x+1)$ of said panels in superposed relation, and

the display panels being provided with enlarged smoothly rounded stiffeners along their edges to rigidify the panels and assure free sliding of the panels successively and by gravity from one end region of the box to the other as the box rotates, whereby $(4x+2)$ different display faces can be brought successively to view through said display openings.

2. A display device as defined in claim 1, in which said display panels are five in number and said rod is of rounded cross-section to facilitate the sliding movements over it of the successive panels.

3. A display device as defined in claim 1, in which the end walls of the box are lined on the interior with cushioning material.

5 4. A display device as defined in claim 1, in which said rod securing means comprises a sleeve encircling the rod, a setscrew in the sleeve adapted separably to engage the rod, and an attachment part carried by the sleeve and secured to the side wall of the box.

10 5. A display device as defined in claim 4, in which said sleeve and attachment part are secured only to the outer 10 of the side wall of the box.

6. A display device as defined in claim 5, in which said 15 sleeve includes a section extending beyond the rod and adapted to receive the end of a driving shaft, said sleeve section being provided with a setscrew for separable engagement with said driving shaft.

7. A display device as defined in claim 1, in which said 20 panel stiffeners are elements having a substantially C-shaped cross-section, each element being slidably applicable to a panel edge to enclose the edge within the confines of the C-shaped element.

8. A device for displaying a plurality of different display panels in a continuous repetitive sequence, comprising: a pair of shallow telescoping sections (13, 14) 25 forming a box (10) adapted to contain an odd number of display panels, each of said sections (13, 14) having a pair of opposed peripheral walls (16, 18), each of said peripheral walls (16, 18) having aligned holes formed therein, a rigid rod (21) inserted through said aligned 30 holes in each of said pairs of telescoped peripheral walls (16, 18) constituting means for locking said sections (13, 14) to each other, means for rotating said rod (21), means (23, 24, and 25) for securing said rod (21) to 35 at least one of said peripheral walls (18) whereby said box rotates with said rod, said rod (21) also constituting means for facilitating the continual sliding of the display panels from one end of the rotating box (10) to the other end of said box (10).
